CLAIM

I claim the ornamental design for a model vehicle body washer, as shown and described.

DESCRIPTION

FIG. 1 is an upper, left, front perspective view of a model vehicle body washer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof; and,

FIG. 7 is a lower plan view of the model vehicle body washer.

The broken lines in the drawings illustrate portions of the model vehicle body washer that form no part of the claimed design.
